UNITED STATES PATENT OFFICE

2,456,152

STERILE DISTRIBUTION AND DRAWOFF SYSTEM

Robert H. Schneider, Madison, Wis., assignor, by
mesne assignments, to Air Reduction Company,
Incorporated, a corporation of New York

Application July 14, 1944, Serial No. 544,993

6 Claims. (Cl. 21—103)

1

This invention relates to a sterilizing system for hospitals and clinics. In such institutions it is quite imperative to have readily available certain fluids that previously have been, and at the moment of use are, thoroughly sterilized. Heretofore it has been necessary for hospital or clinic attendants desiring sterile fluids to get them directly from the sterilizer. The point at which use is to be made of the sterile fluid is often at some distance from the location of the sterilizer. Not only has that entailed frequent and sometimes extended trips to and from the sterilizer for the attendants, but the sterile fluid obtained at the sterilizer is subjected to contamination during the transportation from the sterilizer to the point where the sterile fluid is to be used.

The main objects, therefore, of this invention are to provide a sterile distribution and draw-off system so arranged as to permit a sterile fluid as it is needed to be drawn from any one of several outlets each located near a point at which the sterile fluid is required for use and hence all remote from the sterilizer; to provide an improved construction of a sterile distribution and draw-off system having a number of valve-controlled draw-off faucets all so connected with the sterilizer that the entire conduit system and all of the valve-controlled draw-off faucets are continuously subjected to sterilization; to provide an improved arrangement of connections at the turns of concentric conduits for such a sterile distribution system in order to insure the continuous coextensive relationship of said conduits necessary to provide effective sterilization of all parts of the system; and to provide improved valve-controlled draw-off faucets each operable with one hand for obtaining the desired sterile fluid.

In the specific embodiment of the invention herein shown, Figure 1 is a diagrammatic view showing the sterile distribution system arranged with two draw-off faucets;

Figure 2 is a cross-sectional view of the conduit system taken on the line 2—2 of Figure 1;

Figure 3 is a plan view of the improved form of valve-controlled draw-off faucet;

Figure 4 is an enlarged cross-sectional view taken on the line 4—4 of Figure 3 of the improved draw-off faucet and the arrangement of various connections in the conduit system necessary in order to provide for the various turns in the sterile distribution system and for the attachment of a draw-off faucet.

A sterile distribution and draw-off system constructed in accordance with this invention involves the use of a sterilizer 5 from which lead

5 distributing conduits 6 to several draw-off faucets 7. It generally being necessary to depend upon gravity feed for conducting the sterile fluid to the draw-off faucets, the sterilizer 5 is located on one of the upper floors of the building wherein the system is installed. From here, the distributing system 6 leads around the building and through floors and walls to the draw-off faucets 7 located in various rooms or at various places on one or more of the floors below that on which the sterilizer 5 is located.

10 The sterilizer 5 is of the conventional type involving a tank 8 mounted on a standard or base 9 and equipped with a suitable heating means, such as a conventional gas burner 5', fluid supply, and control valves. None of this regular sterilizer equipment is shown since it forms no part of this invention.

15 The distributing system 6 comprises a pair of 20 concentrically-arranged conduits 10 and 11, the inner one being for conducting the sterilizing medium and the outer one being for conducting the sterile fluid. In this particular embodiment, the conduit 10 is connected to the upper end of 25 the sterilizing tank 8 so that the steam generated therein serves as the sterilizing medium flowing through the conduit 10. Where desired, this conduit 10 could be connected to a source other than 30 the tank 8 for furnishing the sterilizing medium, as, for example, the steam supply for the building, which might also be used for sterilizing the fluid in the tank 8.

35 The draw-off faucet 7 herein shown embodies the invention disclosed in the co-pending application of Floyd A. Blashfield, Serial No. 533,941, filed May 3, 1944 which has matured into Patent No. 2,381,031. This comprises a housing 12 wherein is formed a partition 13 which divides the interior into compartments or chambers 14 and 15, communication between which is controlled by a valve mechanism 16 and from the latter of which communication is controlled by a valve mechanism 17. Both of the valves are operated by a handle 18 so that as occasion demands sterile fluid from the tank 8 flowing through the conduit 11 into the compartment 14 may be discharged through the outlet port 19 into a suitable receptacle.

40 Through the medium of a stem 20 and a concentrically-arranged terminal tube 21, the chambers 14 and 15 of the housing 12 are connected 45 respectively with the conduits 11 and 10 of the distributing system 6. The stem 20 is integral with the housing 12 and supports it on one of the 50 cross fittings 49 as hereinafter more fully set

forth. The terminal tube 21 is supported at one end in the fitting 49 and has its inner end extending through the partition 13 so as to communicate directly with the chamber 15.

A plate 22 secured to the bottom of the housing has formed therein the sterile fluid outlet 19 and a drain 23, which is connected to the pipe 56 leading to the steam trap or the like 57. The sterilizing medium is removed from the housing chamber 15 through this arrangement.

The valve mechanism 16 comprises a valve member 24 urged by a spring 30 onto the valve seat 25 to close the opening 26 through the partition 13. The valve member 24 is supported on a stem 27 slidably mounted in a cap 28 screwed onto a threaded head 29 integral with the housing 12. The spring 30 surrounds the stem and presses between the cap 28 and a shoulder 31 to seat the valve member 24 on the seat 25.

A bellows 32 encloses the valve stem 27 and spring 30 so as to prevent the contact thereof with the sterile fluid in the compartment 14.

A knob or head 33 is secured to the upper end of the stem 27 by means of a set screw 34 whereby the valve member 24 may be unseated through the operation of the handle 18 as will more fully hereinafter appear.

The valve mechanism 17 comprises a valve member in the form of a disc 35 actuated by a shaft 36 rotatably mounted at one side of the housing 12 and on which the handle 18 is mounted, so that it may be shifted in a horizontal plane into and out of position to cover the outlet port 19 in the plate 22.

A pin 37 on the disc 35 extends through an opening near the end of the arm 38 which in turn is keyed to the shaft 36. A spring 39 interposed between the disc 35 and the arm 38 presses the disc 35 into contact with the inner surface of the plate 22. The disc 35 closes or opens the outlet port 19 when the disc 35 is shifted from one to the other of its positions.

A torsion spring 40 embraces the shaft 36 above the arm 38 and has the end 41 thereof secured to the housing 12 and the other end 42 secured against the arm 38 so as to normally shift the disc 35 into position to close the outlet 19.

The handle 18 is formed with a bifurcated head 18' whereby it is pivoted at 43 on the upper end of the shaft 36 and is provided with a lug 44 which is adapted to come into position under the knob or head 33 of the valve mechanism 16 for retracting the valve member 24 when the handle 18 is depressed on its pivot 43 after having first been shifted horizontally against the action of the spring 40 for the purpose of retracting the disc 35 from the outlet 19. A spring 45, arranged in a recess in the handle head 18', bears against the shaft 36 and normally lifts the outer end of the handle so that the extension 44 is held out of position to engage the knob 33 on the valve mechanism 16.

A pin 46 is located on the outer rim of the housing 12 in position to engage the underside of the handle head 18' and prevent the vertical shifting thereof on the pivot 43 until the handle has been shifted horizontally to bring the extension 44 under the knob or head 33 of the valve mechanism 16.

In order to make possible the location of several sterile draw-off faucets at points remote from the sterilizer 5 and insure the sterilization of the conduits and the draw-off faucets, special connections have been developed for the concentrically-arranged conduits to permit changes

in the course of the distributing system 6 and provide branches therefrom for the draw-off faucets 7. At 47 is shown a type of connection required either at a point where the general course of the conduits is changed or at their terminal, which latter may or may not be equipped with a draw-off faucet 7. At 48 is shown the connection required where the distributing system has to be interrupted for the installation 10 of a draw-off faucet 7. Both of these connections 47 and 48 are shown in enlarged cross section in Figure 4.

The connections 47 and 48 involve the use of a standard cross fitting 49 which in every case is connected with the outer conduit 11 or its branches to provide for the continuous flow of the sterile fluid through the system. In order to have the sterile fluid constantly subject to sterilization, the inner conduit 10 is extended through the cross and beyond the opposite opening and then returned through an opening at right angles. Standard fittings are used to support and seal the inner conduit 10 in these cross fittings. As shown in the drawings, these supporting and sealing fittings comprise nipples 50 which are threaded to screw into bushings 51 in the cross fittings 49 and to support threaded nuts 52 which are turned up to compress the packings 53 against the conduit.

As will be noted from the figures, the connection 47 simply involves the running of the conduit 10 out through one opening of a cross fitting 49 and extending it back through the opening at a 90° angle. With the connection 48, it is necessary to provide a T 54 so as to not only return the conduit back through the fitting, from out of which it is extended, but also to provide another branch to cut around and enter a fitting to which is connected the conduit 11 which continues the distributing system 6 beyond a draw-off faucet 7.

The operation of the system herein shown obviously involves the heating of the sterile fluid in the tank 8 by whatever heating means may be most convenient. Once that has been accomplished, suitable valves, not herein shown, are operated to open communication between the sterilizer and the distributing system 6. Sterile fluid will thereupon flow through the conduit 11 to and be available instantly at all of the draw-off faucets 7. Likewise, the sterilizing medium, which in most cases would be steam, will flow through the conduit 10 to the draw-off faucets and keep the sterile fluid in the conduit 11 and the draw-off faucets always sterile.

At the draw-off faucets, the sterile fluid, of course, flows into the chamber 14 through the stem 20. On the other hand, the sterilizing medium flowing through the concentrically-arranged terminal tube 21 not only keeps the sterile fluid in the chamber 14 sterile, but sterilizes all of the parts of the valve mechanism 17 located in the chamber 15. The only part of the entire system that is not directly subjected to the sterilizing medium is the outlet port 19. However, the heat in the chamber 15 will be sufficient to keep the port 19 adequately sterilized.

When a hospital or clinic attendant desires a quantity of sterile fluid a receptacle for receiving such fluid may be held in one hand and, with the other hand, the attendant shifts the handle 18 horizontally in the direction of the arrow 55 (see Figure 3) so as to rotate the shaft 36 for the purpose of swinging the arm 38 to retract the disc 75 valve 35 and uncover the outlet 19. When the

handle 18 reaches the limit of this horizontal movement, the head 18' has been moved out of contact with the pin 46. Moreover, the lug 44 has been brought into position under the head or knob 33 on the stem 27 of the valve mechanism 16. Thereupon, the attendant may depress the handle 18 in a vertical plane causing the lug or extension 44 to contact the head or knob 33 and elevate the valve member 24. The retracting of the valve member 24 permits the sterile fluid to flow through the port 26 and directly out through the outlet 19 into the container held by the attendant. It will be appreciated, of course, that the sterilizing medium, by any appropriate means, is not permitted to enter chamber 15 while sterile fluid is being withdrawn from chamber 14.

As soon as the desired quantity of the sterile fluid has been obtained, the attendant releases the handle 18. Thereupon, the spring 45 elevates the handle so as to bring the head 18' above the pin 46 and at the same time retract the lug 44 from engagement with the head or knob 33. Immediately, the spring 30 will snap the valve member 24 back onto its seat 25 thereby closing off communication between the chamber 14 and the outlet 19. As soon as the handle has been fully elevated by the spring 45, so that the head 18' is above the pin 46, the torsion spring 40 acts on the shaft 36 so as to swing the handle 18 in a horizontal plane, opposite the direction shown by the arrow 55 (see Figure 3), and move the disc valve 35 to close the outlet 19.

Changes in the described structure may be made without departing from the spirit of the invention, the scope of which should be determined by reference to the following claims, the same being construed as broadly as possible consistent with the state of the art.

I claim:

1. The combination with a building having a plurality of separate compartments formed in the interior thereof, of an apparatus for supplying water in a sterile condition to said compartments, said apparatus including a source of sterile water, at least one draw-off faucet in each of said compartments, a conduit system connecting said faucets to said source of sterile water, and means for maintaining the water in sterile condition while in the conduit system and faucets, said conduit system comprising a plurality of pipe sections, cross fittings connecting the sections one to another, the faucets being connected to certain of the cross fittings, each of said cross fittings having two pairs of aligned openings, the axes through said pairs of aligned openings being arranged at an angle to each other, at least two of the adjacent openings in each cross fitting receiving each an end of a pipe section for connecting such sections, said maintaining means comprising a source of steam associated with said container, and piping extending from the source of steam and through the conduit system to the faucets, the piping being directed from one conduit section into a cross fitting secured thereto and out through the opening in said cross fitting aligned with said one conduit section and then being directed through the second pair of openings in the cross fitting into the other conduit section connected to said cross fitting.

2. The combination with a building having a plurality of separate compartments formed in the interior thereof, of means for supplying water in a sterile condition to said compartments, said means including a source of sterile water and a source of steam, at least one draw-off faucet in

each of said compartments, and a conduit system connecting said faucets to said sources of sterile water and steam, said conduit system comprising a plurality of inner and outer pipes, connected, respectively, in sections, the connected inner pipes being connected to one of said sources and conducting the fluid therefrom to said faucets and the connected outer pipes being connected to the other of said sources and conducting the fluid from said other source around the connected inner pipe sections, to said faucets.

3. The combination with a building having a plurality of separate compartments formed in the interior thereof, of means for supplying water in a sterile condition to said compartments, said means comprising a sterilizer, means for boiling water in said sterilizer to provide sterile water and steam, at least one draw-off faucet in each of said compartments, and a conduit system connecting said faucets to said sterilizer, said conduit system comprising a plurality of inner and outer pipes connected, respectively, in sections, the connected inner pipes being connected to the steam section of said sterilizer and conducting steam therefrom to said faucets, and the connected outer pipes being connected to the water section of said sterilizer and conducting sterile water therefrom, around the connected inner pipe sections, to said faucets.

4. A sterile-fluid distributing system comprising a structure providing a container for a sterile fluid and a source of sterilizing medium, a plurality of draw-off faucets, a pair of pipe systems, one positioned in part within the other, connecting said faucets with said structure and each formed of a plurality of connected pipes, the outer pipe system conducting the sterile fluid to said faucets, the inner pipe system being connected to said source of sterilizing medium and conducting the sterilizing medium to said faucets, said pipe systems each including three sections successively in angular relation to one another, a first cross fitting having two pairs of oppositely-disposed openings therein, one end of an outer pipe of the first section being fitted into one opening of one of said pairs of openings and one end of an outer pipe of the second section being fitted into one opening of the other of said pairs of openings, the inner pipes of said first and second sections, respectively, extending through the openings of said one and said other of said pairs of openings and beyond the cross fitting, means to seal the extended ends of said inner pipes of said first and second sections into the other openings of said pairs of openings, a T-shaped fitting having three openings therein, the extended end of one of said inner pipes being connected into one of said openings of said T-shaped fitting, the extended end of the other inner pipe being connected to another opening in said T-shaped fitting, a second cross fitting having two pairs of oppositely-disposed openings therein, the other end of the outer pipe of said second section being fitted into one opening of one of said pairs of openings of said second cross fitting and one end of the outer pipe of the third section being fitted into one opening of the other of said pairs of openings of said second cross fitting, the inner pipe of each of said second and third sections, respectively, extending through the openings of said one and said other of said pairs of openings of said second cross fitting and beyond said second cross fitting, means to seal the extended end of the inner pipe of said third section into the opening of said second cross fitting and opposite the opening therein to which the

outer pipe of said third section is fitted, means connecting one of said faucets to the opening in said second cross fitting opposite the opening in which the outer pipe of the second section is fitted and to the inner pipe of the second section, means connecting another of said faucets to the distal ends of the inner and outer pipes of said third section, and means to connect the extended end of the inner pipe of said third section to the third opening in said T-shaped fitting, whereby continuous inner and outer passages to the faucets are provided and the sterile fluid is maintained in such condition throughout the system.

5. A fluid-conducting system comprising inner and outer pipe systems, the inner pipe system being positioned at least in part within the outer pipe system, said inner and outer piping systems each being formed of connected pipes and each including three sections, a first cross fitting having two pairs of oppositely-disposed openings therein, one end of an outer pipe of the first section being fitted into one opening of one of said pairs of openings and one end of an outer pipe section of the second section being fitted into one opening of the other of said pairs of openings, the inner pipes of said first and second sections, respectively, extending through the openings of said one and said other of said pairs of openings and beyond the cross fitting, means to seal the extended ends of the inner pipes of said first and second sections into the other openings of said pairs of openings, a T-shaped fitting having three openings therein, the extended end of one of said inner pipes being connected into one of said openings of said T-shaped fitting, the extended end of the other inner pipe being connected to another opening in said T-shaped fitting, a second cross fitting having two pairs of oppositely-disposed openings therein, the other end of the outer pipe of said second section being fitted into one opening of one of said pairs of openings of said second cross fitting and one end of the outer pipe of the third section being fitted into one opening of the other of said pairs of openings of said second cross fitting, the inner pipe of each of said second and third sections, respectively, extending through the openings of said one and said other of said pairs of openings of the second cross fitting and beyond said second cross fitting, means to seal the extended end of the inner pipe of said third section into the opening of said second cross fitting opposite the opening therein to which the outer pipe of said third section is fitted, means to connect the extended end of the inner pipe of said third section to the third opening in said T-shaped fitting, a third cross fitting having two pairs of oppositely-disposed openings therein, the outer pipe of the fourth section being connected to the opening of said second cross fitting opposite the opening to which the outer pipe of said second section is connected and to one of the openings of one of the pairs of openings of said third cross fitting, the inner pipe of the second section being extended to form the inner pipe of the fourth section and being sealed into and extending beyond the opening of said third cross fitting opposite the opening to which the outer pipe of the fifth section is connected, and means joining the extended ends of the inner pipes of said fourth and fifth sections, whereby continuous inner and outer passages are provided.

6. A fluid-conducting system comprising inner and outer pipe systems, the inner pipe system being positioned at least in part within the outer pipe system, said inner and outer piping systems each being formed of connected pipes and each including five sections, a first cross fitting having two pairs of oppositely-disposed openings therein, one end of an outer pipe of the first section being fitted into one opening of one of said pairs of openings and one end of an outer pipe section of the second section being fitted into one opening of the other of said pairs of openings, the inner pipes of said first and second sections, respectively, extending through the openings of said one and said other of said pairs of openings of the second cross fitting and beyond said second cross fitting, means to seal the extended end of the inner pipe of said third section into the opening of said second cross fitting opposite the opening therein to which the outer pipe of said third section is fitted, and means connecting the extended end of the inner pipe of said third section to the third opening in said T-shaped fitting, whereby continuous inner and outer passages are provided.

respectively, extending through the openings of said one and said other of said pairs of openings and beyond the cross fittings, means to seal the extended ends of the inner pipe of said first and second sections into the other openings of said pairs of openings, a T-shaped fitting having three openings therein, the extended end of one of said inner pipes being connected into one of said openings of said T-shaped fitting, the extended end of the other inner pipe being connected to another opening in said T-shaped fitting, a second cross fitting having two pairs of oppositely-disposed openings therein, the other end of the outer pipe of said second section being fitted into one opening of one of said pairs of openings of said second cross fitting and one end of the outer pipe of the third section being fitted into one opening of the other of said pairs of openings of said second cross fitting, the inner pipe of each of said second and third sections, respectively, extending through the openings of said one and said other of said pairs of openings of the second cross fitting and beyond said second cross fitting, means to seal the extended end of the inner pipe of said third section into the opening of said second cross fitting opposite the opening therein to which the outer pipe of said third section is fitted, means to connect the extended end of the inner pipe of said third section to the third opening in said T-shaped fitting, a third cross fitting having two pairs of oppositely-disposed openings therein, the outer pipe of the fourth section being connected to the opening of said second cross fitting opposite the opening to which the outer pipe of said second section is connected and to one of the openings of one of the pairs of openings of said third cross fitting, the inner pipe of the second section being extended to form the inner pipe of the fourth section and being sealed into and extending beyond the opening of said third cross fitting opposite that to which the outer pipe of the fifth section is connected, and means joining the extended ends of the inner pipes of said fourth and fifth sections, whereby continuous inner and outer passages are provided.
